UNITED STATES PATENT OFFICE.

ABEL D. TYLER, JR., OF BROCKTON, MASSACHUSETTS.

TRANSVERSELY-DIVIDED BOOT OR SHOE LAST AND UNION THEREFOR.

SPECIFICATION forming part of Letters Patent No. 697,044, dated April 8, 1902.

Application filed July 26, 1901. Serial No. 69,768. (No model.)

To all whom it may concern:

Be it known that I, ABEL D. TYLER, Jr., a citizen of the United States, residing at Brockton, in the county of Plymouth and State of Massachusetts, have invented certain new and useful Improvements in Transversely-Divided Boot or Shoe Lasts and Unions Therefor, of which the following is a specification, reference being had therein to the accompanying drawings.

Figure 1 is an elevation of the inside of a last embodying my invention, a portion of the inside of the last being broken away in part for greater clearness. Fig. 2 is an elevation of the outer side of the last, the outer side of the last being broken away in part for greater clearness. Fig. 3 is a top plan view of the last, the upper portion of the heel part and the comb and instep portion being broken away for greater clearness, and particularly to show the pair of flanged disks and intermediate separator, said disks and separator constituting my new union for connecting the fore part and heel part. Fig. 4 is a lengthwise section of the heel part and fore part at line 4-4 of Fig. 3, the union being removed so as to show the configuration of the union-receiving chamber, which is partially in the heel part and partially in the fore part. Fig. 5 is a diametrical section of the pair of flanged disks and separator which constitute my new union. Fig. 6 is a front elevation of a portion of the inner end of the fore part.

The object of my invention is to produce a strong, durable, transversely-divided last or comparable device which is cheaper to manufacturers than those now in use.

In the drawings illustrating the principle of my invention and the best mode now known to me of applying that principle, 1 is the heel part and 2 the fore part, the fore part and heel part being relatively movable one in relation to another to shorten the last when a boot, shoe, or the like is put on or taken off the last. The heel part 1 is shown with the usual spindle-socket 3, the purpose and uses of which are too well known to require description. The fore part and heel part are divided from the apex 4 of the usual top recess 5, which permits the swinging movement of the

fore part and heel part one in relation to the other to the bottom of the last, the opposed end walls 6 6 of the fore part and heel part abutting against each other below apex 4 when the fore part and heel part are in alinement. These contacting end walls constitute reciprocal bearing-surfaces and give requisite solidity to the last as a whole to enable it to withstand the pressures to which it is subjected when a shoe is on it and the shoe is operated on by such machines as sole-levelers, beaters-out, &c. The apex 4 is about half-way down to the bottom of the last, so that the last will be self-sustaining in respect of endwise pressures thereon in a manner already well known to those skilled in this art.

Heretofore the fore parts and heel parts have been commonly connected by hinges of various kinds, and also, as shown in my Patent No. 655,314, of August 7, 1900, by a ring-shaped guide. The latter construction is cheaper to make than any hinged construction with which I am familiar, and yet it is very desirable to reduce the cost of manufacture still further if it can be done consistently with requisite strength and durability.

In accordance with my present invention heel part 1 is provided with a recess 7, which extends from its inner end rearwardly and is of a width at least equal to the thickness 8c at the flange 8 of both flanged disks 9 9, which are of any suitable material—such as pressed steel, for example. Each opposite side wall 10 10 of recess 7 is formed with a circular groove 11, in which a portion of each flange 8 is received, preferably snugly, so that the flanges and therewith contacting walls of the grooves 11 will have frictional engagement when all the parts of the last are assembled and the fore part and heel part 90 are in alinement and the last is subjected to pressures tending to collapse it. The snug contact of the walls of grooves 11 with the flanges 8 will then tend to resist accidental collapsing of the lasts. The inner end of the 95 fore part 2 is formed with a recess 12, which extends toward the toe of the fore part, is opposed to recess 7, and is of a width corresponding thereto. Each opposite side wall 13 of recess 12 is formed with a circular 100

groove 14, which corresponds to and is, in effect, a continuation of the circular groove 11 in the heel part. The heel part recess 7 and two grooves 11, with the corresponding fore part recess 12, and two grooves 14, form a chamber that receives my new union, comprising the two flanged disks 9 and intermediate separator 15, the flange 8 of each disk being mounted in the supplementary grooves 11 and 14. Separator 15 is a snug fit between the opposed walls of the disks 9, so that the disks are held snugly in place, with their respective flanges extending toward opposite sides of the last when the parts thereof are assembled. The separator is put in from the upper side of the last after the flanged disks are mounted, with the flanges in the flange-receiving grooves, and, if desired, the disks and intermediate separator may be secured together by the transverse fastener 16, conveniently inserted after the parts are assembled through the transverse opening at apex 4, in which a dowel 19 may be placed. I have not, however, found this fastener to be essential.

If desired, transverse dowels 19 may be mounted at or below the apex 4 of the top recess 5 on one or the other of the contacting end walls of the fore part and heel part, such dowels projecting beyond the surface of the end wall on which they are fixed and fitting into corresponding recesses 18 in the face of the opposed end wall. By this means the fore part and heel part engage one with the other when brought into alignment, and the engagement of the transverse dowels with the dowel-receiving recesses 18 tends to prevent deformation of the last in consequence of any twisting strains to which they may be subjected when in use; but I have not thus far found the dowels essential and do not regard them as a necessary part of my invention.

The fore part and heel part are guided, when moved one in relation to the other, by the circular flanges of the disks, the walls of the complementary flange-receiving recesses bearing on the flanges. Somewhat forcible separation of the disks by the intermediate separator helps to maintain the rigidity of the last by forcing the outward walls of the disks against the side walls 10 and 13 of the recesses 7 and 12.

Transversely-divided lasts and comparable structures thus made are strong and durable and practically self-sustaining, with or without the dowels. The requisite chambering of the fore part and heel part for the reception of my new union does not weaken either the fore part or heel part to an appreciable extent. The flanged disks are very cheap to make and the parts are quickly assembled. These are advantages of my present invention on its commercial side. Functionally considered, it will be seen that there is in my present last a very considerable extent of

frictional contacting surface that tends to maintain the fore part and heel part in alignment when the shoe is on the last and the last is subjected to strains that tend to collapse it. The pressure of the outward sides of the disks 70 on portions of the fore part and heel part forming a flatwise disk-pressure and the reciprocal bind of the disk flanges and walls of the flange-receiving grooves form a very strong frictional resistance to collapsing strains, and what may be called the "flatwise" pressure of the disks is peculiarly useful in lasts and the like, because the latter are almost always made of wood, which is so cut that the grain extends in the direction of the length of the 80 last, as indicated, and inasmuch as the flatwise pressure of the outward sides of the disks is at right angles to the grain there is much less liability of splitting my new lasts than there is in many older forms of lasts 85 where strains tending to split the lasts were sometimes exerted on the hinge-leaves inserted, respectively, in fore part and heel part and extending lengthwise of the last in approximate parallelism with the bottom of 90 last and with the grain of the wood. Generally speaking, the relative movements of the fore part and heel part are to shorten the last; but such shortening is old and not an essential part of my invention, although according to present practice now required in 95 all transversely-divided lasts.

The walls 10 and 13 are at right angles to cross-sections of the last—that is, to the last cross-sectionally considered—and in approximate parallelism with the sides of the last.

Having thus described the best form of my invention now known to me, I desire to be understood as claiming my invention in the broadest manner legally permissible.

What I claim is—

1. The combination of the fore part and heel part of a boot or shoe last, or analogous device, with a flanged disk which is mounted in recesses in said parts, connects said parts 110 and permits movement of one part in relation to the other part; and means for keeping said flanged disk in working position.

2. The combination of the fore part and heel part of a boot or shoe last, or analogous 115 device, with a pair of flanged disks which are mounted in recesses in said parts, connect said parts and permit movement of one part in relation to the other part; and a separator inserted between said disks.

3. The combination of the fore part and heel part of a boot or shoe last, or analogous device, with a union which is mounted in recesses in said parts, connects said parts, and permits movement of one part in relation to 125 the other part; said union comprising flat surfaces which contact with opposed fore part and heel part surfaces that are at right angles to transverse sections of the same, and such contact effecting a lateral pressure that re- 130

sists said relative movements of the fore part and heel part, and tends to prevent accidental collapsing of the last, said union comprising a pair of flanged disks, and said recesses being formed with flange-receiving recesses, whereby the heel part and fore part are held in operative relation with each other.

4. A union for boot and shoe lasts, said

union comprising a pair of flanged disks and a separator.

In testimony whereof I affix my signature in presence of two witnesses.
